Atty.

UNITED STATES PATENT OFFICE

THOMAS WILLIAM BYRNE, OF DORCHESTER, MASSACHUSETTS

GOLF-PRACTICE APPARATUS

Application filed January 9, 1928. Serial No. 245,282.

This invention relates to a golf practice apparatus.

The object of the invention is to provide a golf practice apparatus of novel and superior construction with which golf shots may be practiced, and particularly driving shots, and which has provision for recording a measurement of the effectiveness of such shots.

10 A further and more specific object of the invention is to provide a novel apparatus for practicing golf shots, particularly driving shots, which is capable of recording the effectiveness of the shots in accordance with 15 the yardage that would be obtained were the shot to be made upon the golf links.

With these objects in view and such others as may hereinafter appear, the invention consists in the golf practice apparatus hereinafter described and particularly defined in the claims at the end of this specification.

In the drawings illustrating the preferred embodiment of the invention, Figure 1 is a side elevation of the improved golf apparatus; Fig. 2 is a plan of the base; and Fig. 3 is a detail to be referred to.

In general in the present golf practice apparatus a golf ball or similar object which is designed to be struck by the club during the execution of the golf shot is suspended by a flexible connection from a nut mounted upon a threaded rod upstanding from a base member whereby during the execution of the shot the golf ball or similar object upon being struck by the club flies around in a circular path with the threaded rod as a center. The nut being caused to rotate upon the threaded rod is caused to traverse the rod vertically and as a result comes to rest at some point along the threaded rod at a distance from the base proportionate to the effectiveness of the golf shot.

Referring now to the drawings, the apparatus illustrated therein comprises a golf ball 10 mounted upon the end of a pair of

flexible steel spring wires 12. Provision is made for securing the spring wires 12 to a rotatable nut 15 herein shown as comprising a steel sleeve having a pin 13 which is yieldably held in engagement with the threads of a threaded rod 20, and which is arranged to be screwed onto the threaded shaft or rod 20 upstanding from a heavy base portion 22, as shown in Fig. 1. As herein shown, and in order to permit renewal of the steel spring wires, the latter are secured to the nut 15 by a connecting device 24 comprising two clamping plates bolted together. The spring wires 12 are looped around one of the clamping bolts and clamped by one end portion of the connecting device 24, and the connecting device is secured to the nut 15 by a pair of spring wires 27 wound around the nut and the ends of which are clamped between the second end portion of the clamping device in the manner illustrated in Fig. 1. The pin 13 is yieldably held in thread engaging position by a spring strap 30 extended around the sleeve, and an operating handle is provided to permit the pin to be moved outwardly to disengage the threads from the threads of the threaded rod when it is desired to reset the nut to the bottom of the shaft after a shot has been made. The upper end of the shaft is provided with a stop nut for limiting the upward movement of the nut.

In order to record the effectiveness of each golf shot in terms of yardage which would be obtained were the same shot to be made upon the golf links, the length of the steel spring wires 12 are so proportioned and the various positions at which the nut comes to rest after golf shots of certain strength are so made as to enable the face of the threads upon the threaded shaft to be marked by painted dots or otherwise to provide a record of the yardage. For example, the position 50 indicates a drive of 100 yards, the position 52 a drive of 150 yards, the position 53 80

a drive of 200 yards. In addition in the preferred apparatus the threads upon the threaded shaft are proportioned with relation to the length of the spring wires 12 so that each revolution represents additional yardage amounting to 10 yards. The base may be sub-divided from 1 to 10 so that during the use of the apparatus, if the golf ball is positioned so that the steel spring wires 12 are over the numeral 0 upon the base, then upon making a shot the exact yardage can be read down to a single yard.

A rubber bumper comprising a rubber tube is provided in order to protect the club head from engaging the spring wires. In some instances after continued use the spring wires 12 break. At least two of these spring wires 12 are provided in order that a warning may be had of their breaking, because it has been found that one of the wires will break before the other, and in the present apparatus when one of the wires breaks both may be readily renewed. In some instances also it is necessary to renew the wires 27.

While the preferred embodiment of the invention has been illustrated and described, it will be understood that the invention may be embodied in other forms within the scope of the following claims.

Having thus described the invention what is claimed is:

1. A golf practice apparatus comprising a threaded rod, a nut mounted on the rod comprising a sleeve and a pin having a projection on one end for engaging the threads of the rod, yieldable means for holding the pin in engagement with such threads, a golf ball, and a connection between the golf ball and nut.

2. In a device of the kind described, a threaded rod, an elongated nut mounted thereon, a pair of flexible wires carried by the nut at vertically spaced points, a clamping device clamped upon the free ends of said wires, other wires extending from said clamping device and secured thereby, and a golf ball carried by said last wires at the free ends thereof.

3. In a device of the kind described, a vertically disposed threaded rod, a sleeve mounted on said rod and rotatable and slidably thereon, a pin projecting through the wall of the sleeve and engaging the thread of the rod, the outer end of the pin projecting outwardly of the sleeve, a leaf spring having one end fixed on the sleeve and engaging the pin to urge the same inwardly, and a ball carrying arm connected to said sleeve.

4. In a device of the kind described, a vertically disposed threaded rod, a sleeve mounted on said rod and rotatable and slidably thereon, a pin projecting through the wall of the sleeve and engaging the thread of the rod, the outer end of the pin projecting outwardly of the sleeve, a leaf spring having one

end fixed on the sleeve and engaging the pin to urge the same inwardly, a pair of flexible wires connected to the sleeve at vertically spaced points, a clamping device clamped upon the free ends of said wires, other wires extending from said clamping device and secured thereby, and a ball carried by the outer ends of said last wires.

In testimony whereof I have signed my name to this specification.

THOMAS WILLIAM BYRNE.
